AUTOMATIC DAMPING MEANS IN DEFLECTION CIRCUITS

Harry E. Thomas, Montclair, and Sylvester A. DeMars, Ridgewood, N.J., assignors to International Telephone and Telegraph Corporation, Nutley, N.J., a corporation of Maryland

Application February 25, 1955, Serial No. 490,472

7 Claims. (Cl. 250—27)

This invention relates to deflection circuits for cathode ray type electron discharge devices and more particularly to a means for automatically damping oscillations due to reversal of sweep voltages in the output transformer of deflection waveform generators employed in television and like apparatus.

In the output of deflection waveform generators which usually employ transformer coupling, there is generated across the primary winding, a pulse of considerable magnitude when the sweep currents are reversed in the transformer during the retrace portion of the sweep voltage. This is due to the inductive "kick" or voltage across the primary winding inductance. This may cause "ringing" or oscillatory currents which may carry over into the sweep period and affect signal reproduction.

The oscillatory currents established in the output transformer upon reversal of the sweep voltage has in the past been damped by employing the plate resistance of the driver or output electron discharge device or tube as a damping resistor. The damping mechanism, however, is not simple since it requires preshaping of the input sawtooth waveform into a trapezoidal form by what is known commonly as "peaking." This peaking has been accomplished in the past in the sawtooth generator discharge tube circuit by adding a fixed resistance peaking resistor in series with the charging capacitor. The addition of this fixed resistor to a conventional sawtooth generator produces an additional pulse which is superimposed upon the retrace portion of the deflecting waveform. This added pulse determines the plate resistance of the output or driver tube of the deflection system during the retrace portion and the start of the sweep portion of the deflecting waveform to establish the damping effect on the oscillations present in the output transformer.

The amount of damping provided by the driver tube is rather critical. Too much or too little damping will not have the desired effect of suppressing the unwanted oscillations and may affect the retrace time long enough to carry over and affect the linearity of the sawtooth output current near the start of the trace. Even if the fixed resistance peaking resistor has the proper value for desired damping when a given amplitude of synchronizing pulses is present, when a given set of tubes are employed, when a given value of B+ voltage is present, and for a certain setting of the height control in a television receiver, the change of any one of these conditions or a combination of these conditions will vary the amount of damping presented to the oscillations in the output transformer.

Therefore, it is an object of this invention to provide a means to automatically maintain a constant damping of the oscillations occurring in the output transformer of a deflection system.

Another object of this invention is to provide an electronically controlled trapezoidal waveform generator which will automatically provide a constant damping of the oscillation in the output transformer.

A feature of this invention is the provision of a vari-

2

able resistance means in a series relationship with the charging condenser of a sawtooth generator, the resistance of the variable resistance means being controlled to provide a constant damping effect by the output tube of the oscillations occurring in the output transformer of a deflection waveform generator.

Another feature of this invention is the provision of an electron discharge device as the variable peaking resistor of a trapezoidal waveform generator. The peaking of the sawtooth wave generator, and, consequently,

10 the damping effect of the output tube on the oscillations in the output transformer, is controlled by adjusting the bias voltage of the peaking electron discharge device proportional to the peak amplitude of the deflection waveform appearing at the output of the deflection system so that automatically the correct amount of damping results regardless of the signals passing through the system.

15 A further feature of this invention is the employment of a peak detector to monitor the peak amplitude of the deflection waveform appearing at the output of the deflection system, the output of the peak detector adjusting the bias of the peaking electron discharge device disposed in serial relation with the charging condenser of a sawtooth generator to provide a variable peaked sawtooth 20 output therefrom to adjust the plate resistance of the output tube in a manner to maintain a constant damping effect on the oscillations within the output transformer regardless of the amplitude of the signals within the deflection system.

25 30 The above-mentioned and other features and objects of this invention will become more apparent by reference to the following description taken in conjunction with the accompanying drawing, the single figure of which illustrates schematically an embodiment of our invention.

35 In the drawing, there is illustrated a portion of a deflection circuit comprising a source of pulses 1 wherein the output therefrom, as illustrated by curve 2, is repetitive at a predetermined rate for control of the operation of a trapezoidal waveform generator 3. For purposes of explanation, the portion of the deflection circuit illustrated is that of a vertical deflection circuit employed in a television receiver and the output of source 1 is repetitive at the field scanning rate. It is to be understood that the automatic damping circuit disclosed herein 40 may be utilized in any comparable deflection system having a similar damping problem.

45 The trapezoidal waveform generator 3 includes therein a normally non-conducting electron discharge device or tube 4 and an RC time constant including charging condenser 5, load resistor 6 and the plate resistance of electron discharge device or tube 7. Resistor 6 also serves to supply voltage from the B+ supply to the anode 8 of tube 4. When a positive synchronizing pulse from source 1 is coupled through condenser 9 to grid 10 of tube 4, the tube becomes conductive. The capacitor 5 at this time immediately discharges to ground through the internal plate resistance of tube 4. Tube 4 behaves like a switch between condenser 5 and ground. When the synchronizing pulse is removed, grid 10 returns to some negative potential cutting off tube 4 and thereby terminating the discharge of condenser 5. Condenser 5 starts to charge toward the value of the B+ supply at an exponential rate depending primarily upon the values of condenser 5 and resistor 6.

of tube 16 substantially in the form as indicated by waveform 17. The peaked sawtooth or trapezoidal waveform will be amplified by tube 16 and coupled to the primary winding 18 of the output transformer 19. To enable the desired automatic control of the damping effect accomplished by the plate resistance of tube 16, a vacuum or semiconductive diode 20 is placed across the secondary winding 21 of output transformer 19. The diode 20 functions as a peak detector whose conduction varies in accordance with the value of the positive pulses occurring in the secondary winding 21. When the amplitude of the output signal increases, the diode 20 conducts a greater current and develops a control signal in the form of a positive bias voltage across resistor 22. This bias voltage acts on grid 23 of tube 7 to increase the conduction therein and thus decreases its plate resistance. The decreased plate resistance results in a decreased amount of peaking in the trapezoidal waveform. The decrease in the amplitude of the peaked portion of the deflection voltage provides a corrective damping effect by raising the bias voltage on grid 15 of tube 16. This increases the conduction therethrough and results in a lower plate resistance for tube 16.

Conversely, a signal amplitude decrease at the secondary winding 21 will decrease the conduction through diode 20, thus, a less positive voltage across resistor 22, and, hence, a less positive bias on grid 23 of tube 7. This results in less conduction through device 7 and an increase in plate resistance therein. A higher plate resistance for tube 7 produces an increased peaking pulse at point 13 which will bias grid 15 of tube 16 more negative resulting in decreased conduction through tube 16 and thus an increase in its plate resistance to provide the necessary corrective damping. This maintenance of constant effective plate resistance assures correct damping on the output transformer 19.

The action above outlined may seem opposite to what may at first be inferred. However, this is reconciled by the fact that as the sawtooth amplitude is increased, the damping effect is also increased due to the tendency of tube 16 to draw anode current under higher voltages. The damping due to plate resistance is a dynamic quantity which depends upon the characteristics of tube 16 during the retrace period. At this time, two opposing actions take place. First, grid 15 is being driven negative by the combined sawtooth and peaking pulse, the net result being an increase of plate resistance. Second, the added effect of the peaking pulse produces a relatively high induced voltage across anode 24 of tube 16. This voltage tends to produce a decrease in plate resistance particularly if any anode current flows. The decrease in plate resistance due to the induced voltage at anode 24 overshadows any increase of plate resistance due to the action of the driving waveform at grid 15.

The above described automatic damping circuit will result in a constant damping effect of the oscillation occurring in the output transformer of a deflection waveform generator due to the sudden reversal of sweep currents therein regardless of amplitude signal variations occurring in the deflection waveform generator. This constant damping provides the advantage of a deflection waveform having uniform retrace and sweep time.

While we have described above the principles of our invention in connection with specific apparatus, it is to be clearly understood that this description is made only by way of example and not as a limitation to the scope of our invention as set forth in the objects thereof and in the accompanying claims.

We claim:

1. A circuit for generating the deflection voltage for a deflection system of a cathode ray type electron discharge device which automatically maintains a constant damping of the oscillations in said deflection system comprising a source of repetition pulse signals, a reactive means to produce a sawtooth waveform having a sub-

stantially linear sweep portion and a retrace portion in synchronism with said pulse signals, a variable resistance means coupled to said reactive means to provide a series circuit to peak said sawtooth waveform during the retrace portion thereof, said series circuit being coupled in shunt relation to said source, an output means including an electron discharge device for coupling the peaked sawtooth waveform from said reactive means, a detector means coupled to the output of said discharge device to develop a control signal in accordance with the peak amplitude of said peaked sawtooth waveform, and means to couple said control signal to said variable resistance means.

2. A waveform generating circuit for a deflection system of a cathode ray type electron discharge device comprising a source of synchronizing pulse signals, a time constant network including a condenser and a variable resistor, said variable resistor being coupled to said condenser to provide a series circuit, said series circuit being coupled in shunt relation to said source, means responsive to said pulse signals to synchronously charge and discharge said time constant network to produce a peaked sawtooth waveform, an output circuit including an electron discharge device to remove the peaked sawtooth waveform from said time constant network for coupling to a deflection system, a peak detector coupled to the output of said discharge device for developing a control signal in accordance with the peak amplitude of said peaked sawtooth waveform, and means to couple said control signal to said variable resistor to vary the resistance thereof proportional to the amplitude level of said peaked sawtooth waveform for control of the peak amplitude of said sawtooth waveform to maintain a substantially constant damping of the oscillations induced in said output circuit regardless of signal variation in said time constant network.

3. A waveform generating circuit for a deflection system of a cathode ray type electron discharge device comprising a source of synchronizing pulse signals, a reference potential, a time constant network including a charging condenser and a first electron discharge device having at least an anode, a cathode and a control grid, the cathode of said first device being coupled to said reference potential and the anode of said first device being coupled to one side of said condenser, means coupled to the other side of said condenser and responsive to said pulse signals to synchronously charge and discharge said time constant network to produce a peaked sawtooth waveform, an output circuit including a second electron discharge device to remove the peaked sawtooth waveform from said time constant network for coupling to a deflection system, a peak detector coupled to the output of said second discharge device for developing a control voltage in accordance with the peak amplitude of said peaked sawtooth waveform, and means to couple said control voltage to the control grid of said electron discharge device to vary the plate resistance thereof inversely proportional to the amplitude level of said peaked sawtooth waveform for control of the peak amplitude of said sawtooth waveform to maintain a substantially constant damping of the oscillations induced in said output circuit regardless of signal variations in said time constant network.

4. A waveform generating circuit for a deflection system of a cathode ray type electron discharge device comprising a source of synchronizing pulse signals, a reference potential, a time constant network including a condenser and an electron discharge device having at least an anode, a cathode and a control grid, the cathode of said discharge device being coupled to said reference potential and the anode of said discharge device being coupled to one side of said condenser, means coupled to the other side of said condenser and responsive to said pulse signals to synchronously charge and discharge said time constant network to produce a peaked sawtooth

waveform, an output circuit to remove the peaked sawtooth waveform from said time constant network for coupling to a deflection system, a unidirectional device and a resistor coupled in a series relationship across the output of said output circuit for developing a control voltage in accordance with the peak amplitude of said peaked sawtooth waveform, and a conductor coupled to the junction of said unidirectional device and said resistor to couple said control voltage to the control grid of said electron discharge device to vary the plate resistance thereof inversely proportional to the amplitude level of said peaked sawtooth waveform for control of the peak amplitude of said sawtooth waveform to maintain a substantially constant damping of the oscillations induced in said output circuit regardless of signal variations in said time constant network.

5. A circuit for generating the deflection voltage for a deflection system of a cathode ray type electron discharge device which automatically maintains a constant damping of the oscillations in said deflection system comprising a first electron discharge device having at least an anode, a cathode and a control grid, said first electron discharge device being normally non-conductive, an anode voltage supply source, a reference potential, a load resistor coupled between said voltage supply source and the anode of said first electron discharge device, a bias resistor coupled between said reference potential and the cathode of said first electron discharge device, a series circuit including a charging condenser and a variable resistance means coupled between the anode of said first electron discharge device and said reference potential, said load resistor and said variable resistance means providing the charging path for said charging condenser, a source of synchronizing pulse signals, means coupling said synchronizing pulse signals to the cathode of said first electron discharge device to render said first electron discharge device conductive in synchronism with said synchronizing pulse signals, the conductive path of said first electron discharge device and said variable resistance means providing the discharge path for said charging condenser to produce a peaked sawtooth waveform, an output means including a second electron discharge device and an output transformer to remove the peaked sawtooth waveform from the anode of said first electron discharge device, the plate resistance of said second electron discharge device damping the oscillations in said output transformer, peak detector means coupled to said output transformer to develop a control signal in accordance with the peak amplitude of said peaked sawtooth waveform and means to couple said control signal to said variable resistance means to vary the resistance thereof inversely proportional to the amplitude level of said peaked sawtooth waveform for control of the plate resistance of said second electron discharge device to maintain a substantially constant damping effect on the oscillations induced in said output transformer regardless of signal variations in the signal at the anode of said first electron discharge device.

6. A circuit for generating the deflection voltage for a deflection system of a cathode ray type electron discharge device which automatically maintains a constant damping of the oscillations in said deflection system comprising a first electron discharge device having at least an anode, a cathode and a control grid, said first electron discharge device being normally nonconductive, an anode voltage supply source, a reference potential, a load resistor coupled between said voltage supply source and the anode of said first electron discharge device, a bias resistor coupled between said reference potential and the cathode of said first electron discharge device, a series circuit coupled between the anode of said first electron discharge device and said reference potential, said series circuit including a charging condenser and a second elec-

tron discharge device having at least an anode, cathode and control grid, the anode and cathode thereof being in series relationship with the charging condenser, said load resistor and said second electron discharge device providing the charging path for said charging condenser, a source of synchronizing pulse signals, means coupling said synchronizing pulse signals to the grid of said first electron discharge device to render said first electron discharge device conductive in synchronism with said synchronizing pulse signals, the conductive path of said first electron discharge device and said second electron discharge device providing the discharge path for said charging condenser to produce a peaked sawtooth waveform, an output means including a third electron discharge device having at least a cathode, an anode and a control grid and an output transformer coupled to the anode of said third electron discharge device to remove the peaked sawtooth waveform from the anode of said first electron discharge device, the plate resistance of said third electron discharge device providing a damping effect for the oscillations in said output transformer, peak detector means coupled to said output transformer to develop a control voltage in accordance with the peak amplitude of said peaked sawtooth waveform, and means to couple said control voltage to the control grid of said second electron discharge device to vary the plate resistance thereof inversely proportional to the amplitude level of said peaked sawtooth waveform for adjustment of the plate resistance of said third electron discharge device to maintain a substantially constant damping effect on the oscillations induced in said output transformer regardless of signal variation in the signal at the anode of said first electron discharge device.

7. A circuit for generating the deflection voltage for a deflection system of a cathode ray type electron discharge device which automatically maintains a constant damping of the oscillations in said deflection system comprising a first electron discharge device having at least an anode, a cathode and a control grid, said first electron discharge device being normally nonconductive, an anode voltage supply source, a reference potential, a load resistor coupled between said voltage supply source and the anode of said first electron discharge device, a bias resistor coupled between said reference potential and the cathode of said first electron discharge device, a series circuit coupled between the anode of said first electron discharge device and said reference potential, said series circuit including a charging condenser and an electron discharge device having at least an anode, cathode and control grid, the anode and cathode thereof being in series relationship with the charging condenser, said load resistor and said second electron discharge device providing the charging path for said charging condenser, a source of synchronizing pulse signals, means coupling said synchronizing pulse signals to the grid of said first electron discharge device to render said first electron discharge device conductive in synchronism with said synchronizing pulse signals, the conductive path of said first electron discharge device and said second electron discharge device providing the discharge path for said charging condenser to produce a peaked sawtooth waveform, an output means including a third electron discharge device having at least an anode, a cathode and a control grid and an output transformer coupled to the anode of said third electron discharge device to remove the peaked sawtooth waveform from the anode of said first electron discharge device, the plate resistance of said third electron discharge device providing a damping effect for the oscillations in said output transformer, a unidirectional device and a resistor in a series relationship coupled across the secondary of said output transformer to develop a control voltage in accordance with the peak amplitude of said peaked sawtooth waveform, and a conductor coupled to the junction of said unidirectional

device and said resistor to couple said control voltage to the control grid of said second electron discharge device to vary the plate resistance thereof inversely proportional to the amplitude level of said peaked sawtooth waveform for control of the plate resistance of said third electron discharge device to maintain a substantially constant damping effect on the oscillations induced in said output transformer regardless of signal variation in the signal at the anode of said first electron discharge device. 10
